[57] CLAIM

The ornamental design for a public access data processor controlled information terminal, substantially as shown and described.

DESCRIPTION

FIG. 1 is a front, right side perspective view of a public access data processor controlled information terminal showing our new design;

FIG. 2 is a front elevational view thereof on an enlarged scale;

FIG. 3 is a side elevational view thereof on an enlarged scale, the opposite side being identical;

FIG. 4 is a top plan thereof; and

FIG. 5 is a bottom plan view thereof.

FIG. 1

FIG. 2

FIG. 3

FIG. 4

FIG. 5
